STORAGE BIN

Harold D. Hulterstrum, Baraboo, Wis., assignor to Flambeau Plastics Corporation, Baraboo, Wis., a corporation of Wisconsin

Filed Aug. 29, 1960, Ser. No. 61,932

Term of patent 14 years

(Cl. D58—12)

I claim:

The ornamental design for a storage bin, substantially as shown.
